S. M. BRYDGES,
CHECK PROTECTOR,
APPLICATION FILED MAY 21, 1917.

1,255,704.

Patented Feb. 5, 1918.

UNITED STATES PATENT OFFICE.

SAMUEL M. BRYDGES, OF VANCOUVER, BRITISH COLUMBIA, CANADA.

CHECK-PROTECTOR.

1,255,704.

Specification of Letters Patent.

Patented Feb. 5, 1918.

Application filed May 21, 1917. Serial No. 169,965.

To all whom it may concern:

Be it known that I, SAMUEL M. BRYDGES, a citizen of the Dominion of Canada, residing at Vancouver, in the Province of British Columbia, Canada, have invented certain new and useful Improvements in Check-Protectors, of which the following is a specification.

This invention relates to a check stamp 10 designed to indelibly mark a check or the like with the exact value in dollars that it is drawn for, as a protection against its value being raised.

Many devices are at present in use for 15 marking checks in this manner for their protection, but the great majority of these are not satisfactory in that they do not mark the check with the exact dollar value for which the check is drawn, but with a round 20 number in excess of that; or, if designed to mark the full dollar value, they are too complicated and too cumbersome for general adoption.

The appliance which is the subject of this 25 application, will not only press the paper of the check with the exact value in dollars and simultaneously ink the impression so that the ink penetrates the ruptured tissue of the paper and renders the mark indelible, 30 but is sufficiently simple and compact in its mechanism that it can, when desired, be adapted to be carried within a check-book for pocket use.

The invention is particularly described in 35 the following specification, reference being made to the drawings by which it is accompanied, in which:

Figure 1 is a longitudinal section on the line 1-1 in Fig. 2 showing the presser bar 40 lever in the raised position and in dot and dash lines as applied to impress a check.

Fig. 2 is a plan of the same with portions of the covers removed.

Fig. 3 is a cross section on the line 3-3 in 45 Figs. 1 and 2 looking in the direction of the arrow 3.

Fig. 4 is a side elevation of the type bar cover plate and inking pad.

Fig. 5 is a cross section of the same on 50 the line 5-5 in Fig. 4, and

Fig. 6 shows in side elevation a modified arrangement of the presser bar lever.

The device comprises a rectangular shallow bordered plate 2 of thin sheet metal, 55 which plate is lengthwise divided into a series of grooves 3 by thin partitions 4 se-

cured to and upwardly projecting from the plate 2. These partitions 4 are interrupted at 20 adjacent their midlength to receive, when the same is folded down out of use, a 60 presser bar 5 secured across the free end of a presser lever 6 hinged at 7 to the frame plate 2.

Within each groove 3 is endwise movable a type bar 8. The end of each bar is extended beyond the presser bar location 20 and has a finger engagement 9 which projects upwardly through a slot 10 in a cover plate 11 which extends across that half of the frame opposite that to which the presser 70 lever 6 is hinged and is secured to the edge border of the plate in any convenient manner.

The upper face of each bar has in relief 75 numeral type from 1 to 0 consecutively arranged from adjacent the finger engaging end backward. The relief faces of these type are deeply grooved lengthwise of the bar and the contacting face of the presser bar 5 is correspondingly grooved with acute 80 angled V notches. Each type bar adjacent the finger engagement has a resilient detent 12 secured to it which is designed to engage one of a series of notches 13 extending across the bottom of its groove 3 and definitely locate the type in correct alinement with one another under the presser bar 5.

Across that section of the grooves 3 wherein the type bars are normally located, that is, at the end under the presser lever 6, a cover 90 plate 14 is connected, the underside of which cover plate has an absorbent material, such as felt, cemented to it to form an inking pad 15. This cover plate 14 is supported on light springs 16 secured to the bottom of the frame 95 2 on each side, which springs engage lugs 17 projecting from the sides of the cover, and is retained in contact with these springs by portions 18 which are split from the springs 16 and turned upward and apertured to receive the lugs 17.

The inking pad 15 of this cover 14 is thereby held clear of the type except when the presser lever 6 is folded down when light springs 19 secured on each side of the 105 presser lever engage the upper side of the lugs 17 and press the inking pad into contact. The lug apertures of 18 are such as will permit this downward inking movement.

Normally the type bars are all at the backward limit of their movement under the

cover plate 14 and the presser lever 6 is folded down with its bar 5 in the space 20 interrupting the partitions 4, in which position it will be noted that the inking pad 15 is pressed into contact with the type. When required for use the presser bar 6 is lifted and each type bar is endwise moved to bring the desired type numbers into alinement at the space 20 under the presser bar. The finger engagement of each type bar has an indicating pointer 21 which may be set to the required number marked along the slots of the cover plate 11 to make the required value for which the check is drawn.

15 The two outer type bars have a series of dollar signs in type outside each numeral type and the intermediate type bars have a similar dollar sign preceding the first numeral of each series, that is, toward the finger engaging end of the bar. Whatever number of dollars the check may be drawn for may thus be preceeded and followed by a dollar sign to prevent addition. When the type are set to the desired number the 20 check is placed across the space 20 and the presser bar is forcibly pressed down, when the type, as set, will be impressed through the paper and the fiber of the paper will be torn or strained apart by the acute V's of the 25 presser bar 5 in the corresponding grooves of the type, so that the ink of the type will penetrate the cut or torn edges of the impression and render it indelible.

30 The type may be made to read the correct impression on the upper face, in which case the setting of the numbers can be more readily seen and the check being placed face upward the value for which the type have been set can be verified at a glance with the written number on the check, and the type numbers being strongly impressed through the paper will be quite legible on the upper face although the ink is applied to the underside. If preferred, however, the type on the bars 35 may be inverted to give the correct impression on the face which comes in contact with them, in which case the check will require to be turned face down while stamping. This, however, is a matter of convenience only and 40 not material to the subject matter of the invention.

45 It will be noted that in the device as described and illustrated the stamping pressure is manually applied direct to the presser bar 5. If it is found desirable to increase this pressure, the hinge 7 of the presser bar lever may, as shown in Fig. 6, be moved closer to the location 20 where the type are alined, and the presser bar 5 will be secured 50 on the lever 6 a corresponding distance from the hinge, so that the manual pressure applied to the end of the lever 6 will be multiplied to the presser bar 5, and impose less effort on the user. It is, of course, desirable 55 that the hinge or fulcrum of the lever 6 be

located at such distance from the stamping location 20 that the bar will reach a sufficient distance beyond the edge of the check.

Having now particularly described my invention, I hereby declare that what I claim 70 as new and desire to be protected in by Letters Patent, is:

1. A check protecting stamp, comprising in combination a base having a series of type bar grooves, a lever frame hinged to the 75 base adjacent to one end, said lever frame having a presser bar secured across it intermediate of its ends, a series of type bars endwise movable in the grooves of the base, said type bars having type in relief arranged 80 along the upper exposed face, a cover supported over the type bars at the backward limit of their movement, said cover having an inking pad secured to its under side, means for resiliently supporting the inking pad clear of the type while permitting it to be pressed into contact therewith, and means for checking movement of each type bar with any of its type in alinement under the 85 presser bar.

2. A check protecting stamp, comprising in combination a base plate lengthwise divided by partitions secured to and upwardly projecting from it to form a series of type bar grooves, a lever frame hinged to the sides of the base plate adjacent one 90 end, said lever having a presser bar secured across it intermediate of its ends, the face of which bar toward the base plate is deeply grooved, a series of type bars endwise movable in the grooves of the base plate each bar having type in relief consecutively arranged 95 along the upper exposed face, the face of said type being deeply grooved to correspond with the grooves of the presser bar, a cover supported over the type bars at the backward limit of their movement, said cover having an inking pad secured to its underside, means for resiliently supporting the inking pad 100 clear of the type while permitting it to be pressed into contact therewith, and resilient means for checking movement of each type bar with any of its type in alinement under the 105 presser bar.

3. A check protecting stamp, comprising 110 in combination a base plate lengthwise divided by partitions secured to and upwardly projecting from it to form a series of type bar grooves, a lever frame hinged to the sides of the base plate adjacent one end to 115 fold over toward the other end, said lever having a presser bar secured to it intermediate of its ends to extend across the upper side of the base plate, the face of said bar toward the frame being acutely serrated or 120 grooved, type bars endwise movable in the grooves of the base plate, said bars having type consecutively arranged endwise on its upper side, the face of which type are deeply 125 serrated or grooved to register with the 130

grooves of the presser bar, an inking pad resiliently supported over the type bars at the backward limit of their movement and susceptible of being pressed into contact 5 therewith, and a resilient detent secured to the end of each type bar and adapted to enter any one of a series of notches in the bottom of the type bar grooves to definitely locate any of the type in alinement under the

10 presser bar.

4. A check protecting stamp, comprising in combination a base plate lengthwise divided by partitions secured to and upwardly projecting from it to form a series of type 15 bar grooves which partitions are interrupted adjacent the midlength of the frame, a lever frame hinged to the sides of the base plate adjacent one end, said lever having a presser bar secured across it at a position corresponding to the interruption of the length- 20 wise partitions of the plate, the face of said

bar toward the frame being acutely serrated or grooved, type bars endwise movable in the grooves of the base plate, said bars having type consecutively arranged endwise on 25 their upper side, the faces of which type are deeply serrated or grooved to register with the grooves of the presser bar, an inking pad resiliently supported over the type bars at the backward limit of their movement and susceptible of being pressed into contact therewith by the presser bar lever when the same is pressed down when the type bars are at the backward limit of their movement, and a resilient detent secured to 30 the end of each type bar and adapted to enter any one of a series of notches in the type bar grooves to definitely locate any of the type in alinement under the presser bar.

35 In testimony whereof I affix my signature. 40

SAMUEL M. BRYDGES.
